UNITED STATES PATENT OFFICE

119,417

DESIGN FOR A MECHANICAL PENCIL OR SIMILAR ARTICLE

Henry Zoll, Elmhurst, N. Y., assignor to Eberhard
Faber Pencil Co., Brooklyn, N. Y., a corpora-
tion of New York

Application January 16, 1940, Serial No. 89,497

Term of patent 14 years

To all whom it may concern:

Be it known that I, Henry Zoll, a citizen of
the United States and a resident of Elmhurst, in
the county of Queens and State of New York,
have invented a new, original, and ornamental
Design for a Mechanical Pencil or Similar Ar-
ticle, of which the following is a specification,
reference being had to the accompanying draw-
ing, forming part thereof.

Figure 1 is a front elevational view of a me-
chanical pencil embodying the new design.

Figure 2 is a side elevational view of the pen-
cil, and

Figure 3 is an enlarged top end view of the
pencil.

I claim:

The ornamental design for a mechanical pencil
or similar article, as shown.

HENRY ZOLL.
